UNITED STATES PATENT OFFICE.

WILLIAM L. GARRELS, OF ST. LOUIS, AND CLINTON KIMBALL, OF KIRKWOOD, MISSOURI.

MOTOR-VEHICLE.

SPECIFICATION forming part of Letters Patent No. 784,486, dated March 7, 1905.

Application filed July 7, 1900. Serial No. 22,810.

To all whom it may concern:

Be it known that we, WILLIAM L. GARRELS, a resident of the city of St. Louis, and CLINTON KIMBALL, a resident of the city of Kirkwood, in the county of St. Louis, State of Missouri, citizens of the United States, have invented certain new and useful Improvements in Motor-Vehicles, of which the following is a specification.

Our invention relates to motor-vehicles, and has for its principal objects to minimize undesirable strains upon and the flexing of any of the parts of the driving mechanism or the framework thereof; also, to regulate the slack and adjustment of the driving-chain; also, to keep the distance between the crank-shaft of the engine and the driving-axle constant for all positions of the body with respect to the running-gear.

Our invention consists in mounting the engine-frame upon hollow trunnions connected to the steam and exhaust pipes, respectively.

It also consists in an adjustable brace or strut extending from the engine-frame to a beam constituting a part of the running-gear.

It also consists in an adjustable case for the driving-chain.

It also consists in an adjustable chain-case constituting a strut between the engine-frame and a beam forming part of the running-gear.

It also consists in combinations and arrangement of parts and in details of construction hereinafter described and claimed.

In the accompanying drawings, which form part of this specification, and wherein like symbols refer to like parts wherever they occur, Figure 1 is a general view of our invention applied to a vehicle. Fig. 2 is a like view showing a modified form of strut between the engine-shaft and the driving-axle casing. Fig. 3 is a view of the chain-case with a part thereof shown in section. Fig. 4 is an enlarged longitudinal sectional detail showing means of adjusting a tubular chain-case. Fig. 5 is a cross-sectional detail of the chain-case and chain on line 5 5 of Fig. 3. Fig. 6 is a horizontal partly-sectional view of a spring-saddle. Fig. 7 is a vertical partly-

sectional view thereof, the section being taken on the line 7 7 of Fig. 6. Fig. 8 is a view of an adjustable strut between the engine-frame and the casing of the driving-axle. Fig. 9 is a view of the engine-shaft and the parts connected thereto, being partly in elevation and partly in longitudinal section. Fig. 10 is a horizontal section through the supporting trunnions and cylinders of the engine on line 10 10 of Fig. 11. Fig. 11 is an elevation of the left-hand casting or portion of the engine shown in Fig. 10; and Fig. 12 is a detail, partly sectional, the section being taken on the line 12 12 of Fig. 10, showing the manner of mounting the engine on the vehicle-body.

Our motor consists of a two-cylinder steam-engine pivotally mounted on the vehicle-body. For this purpose a channel-bar 1 is firmly fixed transversely on the vehicle-body. Upon this channel-bar are fixed a pair of brackets or pipe-hangers 2. Upon these brackets rest the steam-pipe 3 and the exhaust-pipe 4 in alignment with each other. These pipes 3 and 4 are arranged to constitute trunnions for pivotally mounting the entire engine. For this purpose the engine-cylinders have two aligned sockets 5 and 6. These sockets are interiorly screw-threaded and are large enough to permit the steam and exhaust pipes to enter them, respectively. The steam-pipe has an annular flange 7 on its end, and a hollow nut 8, fitting over said steam-pipe, works in the thread of the socket 5, so as to clamp the steam-pipe flange to the engine-cylinders. The joint between said hollow nut 8 and said steam-pipe 3 may be packed by any suitable packing 9. This hollow nut is interiorly threaded and has a gland 10 working therein to compress the packing. Lock-nuts 11 are used upon the hollow nut 8 and upon the gland for locking them in position. By this construction the steam-pipe is clamped to the engine-cylinders by a steam-tight joint, which permits the frame to swivel upon the steam-pipe as upon an ordinary trunnion. The flange construction may be used for connecting the exhaust-pipe to the engine-cylinders; but as the pressure in the exhaust-pipe is com-

paratively low it is unnecessary to use a flange on the end thereof and the hollow nut for co-operating therewith.

The engine-cylinders are preferably made of two separate castings bolted together. One of said castings, 12, contains the socket 5, into which the steam-pipe fits, and the other casting, 13, contains the socket 6, into which the exhaust-pipe fits. The socket 5 is connected by the passage-way 14 to the steam-chest 15, into which the steam-ports 16 open, the passage-way 14 being thereby entirely within the casting 12, thus avoiding a joint in the said steam-passage. The socket 6 is connected by passage-ways 17, partly within the casting 12 and partly within the casting 13, to the exhaust-ports 18 of the cylinders. The advantages of this construction are that one or two steam-chest covers are done away with and that the valve-seats are accessible for scraping.

The crank-shaft 19 of the engine is mounted at the lower end of the engine-frame 20 and is driven by connecting-rods 21, receiving motion from the pistons of the respective engines and connected, respectively, to crank-disks fixed on the ends of said shaft. Near each end of the shaft a bearing-sleeve 22 is fitted thereon, so as to be free to turn in case the friction on its outer surfaces should become excessive, as in case of breakage and binding of the antifriction-balls. Upon each bearing-sleeve are arranged two circular series of antifriction-balls 23, the balls of each series being properly spaced by means of separators or rings 24, having holes in which said balls lie. The outer bearing-surfaces for said balls are provided by beveled rings 25, which are adjusted endwise by means of a flanged case or hollow nut 26, threaded to work in an interiorly-threaded case or bush 27, said rings 25 being free to turn on said hollow nut 26, so that the bearing will be converted from a ball-bearing to an ordinary sliding bearing in case of breakage of balls. Said case or bush 27 is externally threaded, so as to screw into the lower end of the engine-frame 20, and thereby be firmly mounted thereon. A set-nut 28 works on the case 26, so as to set it firmly in any adjusted position. The bush 27 has an inwardly-projecting flange at its inner end, which constitutes an abutment for the innermost ring 25 of the ball-bearing. The outer surfaces of the inner ends of the bushes 27 are of spherical form, said surfaces being in a common sphere. Over said bushes is fitted a casing 29, whose inner surface conforms to the spherical surfaces of said bushes, whereby said bushes and casing constitute, in effect, a ball-and-socket joint. This casing 29 incloses a sprocket-chain 30, which fits over a sprocket-wheel 31, fixed on the crank-shaft 19, and incloses a sprocket-wheel and compensating gear mounted on the driving-axle 32 of the vehicle. Said casing 29 also incloses said driving-axle and is swiveled in the spring-

saddles 33. The chain-case is thus free to oscillate about the axis of the driving-axle. The driving-axle is divided at its middle, and has consequently little strength as a beam. The casing of the driving-axle and compensating gear extends from side bar to side bar and acts as a beam and constitutes part of the running-gear.

The preferred form of the chain-casing is illustrated in Figs. 3, 4, and 5, wherein the spherical portion of the casing which fits over the spherical bushes on the engine-frame is made in two parts bolted together and has tubular extensions 34 for incasing the chain. These tubular extensions are screw-threaded and have threaded sleeves 35 working therein. The other end of said sleeve swivels in a second sleeve 36, and this last-mentioned sleeve 36 is brazed or otherwise fastened into a tube 37, which constitutes a continuation of the chain-case. The sleeve 35 has a shoulder 38, adapted to abut against the end of the sleeve 36 and containing holes to adapt it for manipulation with a wrench. A third sleeve 39 is threaded to fit over the sleeve 36 and has an interior flange 40, adapted to abut against the shoulder 38 and containing holes to adapt it for manipulation with a wrench. By this construction the chain-case is made adjustable in length, the adjustment being effected by screwing the sleeve 35 into or out of the socket 34, according as it is desired to shorten or lengthen the case, and then screwing the sleeve 39 home, whereby the two portions of the casing are rigidly connected together. One of these adjustable connections is inserted in the tube on the driving side of the chain and another is inserted in the tubular case surrounding the slack side of the chain. The chain-case thus forms the mechanical equivalent of a strut acting between the axis of the crank-shaft and the axis of the driving-axle.

It is obvious that a separate strut may be mounted between the engine-frame 20 or casing 41 and the rear axle or casing thereof and that this strut may be made adjustable in length in various ways—as, for instance, by being made in two threaded parts connected by a turnbuckle, as shown in Figs. 2 and 8. In such a construction the tubular members of the chain-case are arranged to telescope with the extensions from the engine-frame member, as shown in Fig. 2. It is desirable where a separate strut is used to connect it by swivels to the axle-case and to the engine-frame 20 or casing 41 and to have a swivel connection in the strut itself at right angles to said first-mentioned swivels.

A convenient means of connecting the axle-casing to the side bars is represented in Figs. 6 and 7. A saddle 33 is mounted to turn on said axle-case. Said saddle has a lateral projecting socket-piece 42, threaded interiorly, and the side bar 43 is made tubular and has a

threaded sleeve 44 fastened in the end thereof. A second sleeve 45, threaded externally, works in the threaded socket-piece 42, and a threaded bolt 46 extends through said sleeve 45 and screws into the sleeve 44 in the side bar, said bolt being inserted through said sleeve 45 before said sleeve 45 is mounted in place. This construction constitutes a swivel-joint in said side bar, as well as a swivel-joint for fastening said side bar to the axle-case. In order to prevent the accidental turning of the sleeve 45 in the socket 42 or the accidental turning of the bolt 46 in the sleeve 44, it is preferable to fasten said sleeve and said bolt by means of pins 47 and 48, extending through the socket-piece and through the side bar, respectively.

It is obvious that one or more universal joints may be placed in each chain-tube and that at the same time a device for adjusting the distance between the sprocket-wheel centers may be placed in each chain-tube. It is also obvious that any form of joint that will permit the ends of the strut to oscillate, may be used in lieu of those shown. Thus in place of the universal joint about the engine-shaft said joint may be replaced by one or more swivel-joints, and the swivel joint or joints about the driving-axle may be replaced by a universal joint. It is also obvious that a single tube or case may be used to incase both the tight and the slack sides of the driving-chain. It is also obvious that in place of the sliding or telescoping sections of the chain-tube, (shown in Fig. 2,) slides about either the engine-sprocket or the driving-axle sprocket may be used.

It is noted that the construction herein claimed and described embodies elements and features claimed in a prior application filed by us January 17, 1900, Serial No. 1,741, to which reference is hereby made for ascertaining such additional claims.

What we claim herein is—

- 45 1. In a motor-vehicle, a driving-motor pivotally mounted on the vehicle-body and operatively connected to an axle of said vehicle, a beam constituting part of the running-gear, and a strut having a spherical socket at its end adapted to fit over a spherical portion of the motor frame or casing, and thereby constitute a ball-and-socket joint, said strut being also pivotally connected to the running-gear to oscillate thereon, substantially as described.
- 55 2. In a motor-vehicle, a driving-motor pivotally mounted on the vehicle-body and operatively connected to an axle of said vehicle, a rigid casing for said axle extending from side bar to side bar and constituting part of the running-gear, and a strut extending from the motor frame or casing to said axle-case and having a universal connection therewith, substantially as described.
- 65 3. In a motor-vehicle, a driving-motor pivotally mounted on the vehicle-body and opera-

tively connected to an axle of said vehicle, a rigid casing for said axle constituting part of the running gear, and a casing for the mechanism connecting said motor to said axle, said last-mentioned casing constituting a strut and 70 being universally connected to the motor frame or casing and to the axle-casing respectively, substantially as described.

4. In a motor-vehicle, a driving-motor pivotally mounted on the vehicle-body, a chain 75 for transmitting power from said motor to the driving-axle of said vehicle, a casing for said chain extending from the frame or casing of said motor to the running-gear, and pivotally connected to one and universally connected to 80 the other, said chain-case constituting a strut for maintaining the distance between the driving-shaft and the axle constant, substantially as described.

5. In a motor-vehicle, a driving-motor pivotally mounted on the vehicle-body, a chain for transmitting power from said motor to the driving-axle of said vehicle, an adjustable case 85 for said chain extending from the frame or casing of said motor to the running-gear, and pivotally or universally connected to them respectively, said adjustable chain-case constituting a strut for maintaining the distance between the driving-shaft and the axle constant, 90 substantially as described.

6. In a motor-vehicle, a driving-motor pivotally mounted on the vehicle-body, a chain for transmitting power from said motor to the driving-axle of said vehicle, a casing for said chain extending from the frame or casing of said motor to the running-gear, and pivotally connected to one and universally to the other, said chain-case constituting a strut for maintaining the distance between the driving-shaft and the axle constant, said strut consisting of 100 tubular sections, each section having a threaded sleeve working therein, said sleeve being arranged to telescope in a second sleeve having a shoulder thereon, and a third sleeve 105 threaded to work on a thread on one of said first-mentioned sleeves, and having a flange adapted to interlock with a shoulder on one of said sleeves, substantially as described.

7. In a motor-vehicle, a strut operatively connected to the motor-sprocket and to 115 sprocket to be driven thereby and a chain-case comprising telescoping members operatively connected to said sprockets, substantially as described.

8. In a motor-vehicle, a steam-engine pivotally suspended on hollow trunnions adapted to communicate with the admission and exhaust ports of said engine respectively, said engine being operatively connected to the driving-axle, and a casing for the power-transmitting mechanism, said casing being arranged to position the engine, substantially as described.

9. In a motor-vehicle, a steam-engine pivotally suspended on hollow trunnions con- 130

nected with the steam and exhaust ports of said engine respectively, the cylinders of said engine being made in two castings arranged to form the valve-chest, substantially as described.

10. In a motor-vehicle, an engine pivotally suspended on hollow trunnions connecting with the steam and exhaust ports of said engine respectively, the cylinders of said engine being made in two castings adapted to form the valve-chest, and one of said castings containing the entire passage-way from the steam-pipe to the steam-chest, substantially as described.

15. 11. In a motor-vehicle, a steam-engine piv-

otally suspended from hollow trunnions connecting with the steam-port and exhaust-port of said engine, the connection on the steam side consisting of a flanged steam-pipe bearing against a shoulder in a socket formed in one of the engine-castings, a hollow nut working in a thread in said socket and bearing against said flange, and means for packing said joint, substantially as described. 20
